UNITED STATES PATENT OFFICE.

JOHN B. MACNEILL, OF WILKINSBURG, PENNSYLVANIA, ASSIGNOR TO WESTINGHOUSE ELECTRIC AND MANUFACTURING COMPANY, A CORPORATION OF PENNSYLVANIA.

CIRCUIT-INTERRUPTER.

1,241,533.

Specification of Letters Patent.

Patented Oct. 2, 1917.

Application filed August 10, 1916. Serial No. 114,161.

To all whom it may concern:

Be it known that I, JOHN B. MACNEILL, a citizen of the United States, and a resident of Wilkinsburg, in the county of Allegheny and State of Pennsylvania, have invented a new and useful Improvement in Circuit-Interrupters, of which the following is a specification.

My invention relates to circuit interrupters and particularly to automatic circuit interrupters that are provided with means for preventing their closure when the conditions in the circuit are such as to normally cause them to open.

The object of my invention is to provide a device of the above indicated character that shall have only a single latch for securing its operating arms together, be cheap to construct and positive and effective in its operation.

Heretofore it has been the custom to provide a contact-carrying lever, an actuating lever, a latch for holding them together and a second latch for securing the actuating lever to a stationary member. The latches were so arranged that the tripping of one automatically released the other. Such devices, while effective, were expensive to construct and difficult to adjust. In view of the above, I provide two levers having cam surfaces near their outer ends, a latch for latching them together and a spring-restrained pin or cam member that is adapted to become so wedged between the cam surfaces as to hold the levers in their closed positions until one of the levers is released by automatic or manual means.

In the accompanying drawings, Figure 1 is a side view, partially in section and partially in elevation, of a device embodying my invention, and Fig. 2 is a top plan view of the device shown in Fig. 1.

A circuit interrupter 1 comprises movable and stationary contact members 2 and 3, an operating mechanism 4, a tripping device 5, and an accelerating and retarding means 6 for the movable contact members 2.

The operating mechanism 4 comprises an operating electromagnet 7 having a stationary magnetizable core member 8, a movable core member 9 and a winding 10. A lever arm 11 is pivotally mounted on a pin 12 that is supported by brackets 13 on the stationary core member 8 of the electromagnet 7. The movable contact members 2 of the

circuit interrupter 1 are supported by a rod 14 that is operatively connected to one end 15 of the lever 11 which is provided with a cam surface 16 at its other end and with a pin 17 that is disposed across an opening 18 therein. A two-part lever 19 is also pivotally mounted on the pin 12 and its two arms are disposed on the respective sides of the lever 11. The movable core member 9 of the electromagnet 7 is operatively connected, through a pin 20, to the lever 19. A latch 21 is supported on a bracket 22 on one end of the lever 19 and is provided with a projection 23 which is adapted to be normally held in such position by a spring 24 that the latch 21 engages the pin 17 in the lever 11 to hold the levers together. The bracket 22 is provided with inwardly extending projections 25 for purposes hereinafter set forth.

The tripping electromagnet 5 is mounted on the stationary core member 8 of the electromagnet 7 and comprises a stationary core member 26, a movable core member 27 and a winding 28. The movable core member 27 is provided with a tripping rod 29 that is adapted to engage the projection 23 on the latch 21 for the purpose of unlatching the levers 11 and 19 from each other, under predetermined conditions.

The combined accelerating and retarding device 6 is mounted upon brackets on the magnetizable core member 8 of the electromagnet 7 and comprises a casing 30, a piston 31, a rod 32 and a spring 33. The rod 32 is operatively connected, at one of its ends, to the lever 11 and, at its other end, to the piston 31. The spring 33 is disposed between the piston 31 and a cover 34 of the casing 30. The spring 33 is adapted to accelerate the disengagement of the contact members 2 and 3, and the piston 31 is adapted to cooperate with the casing 30 for the purpose of retarding the movement of the contact members 2 toward the latter part of their movement.

A member 35 is pivotally mounted on a bracket 36 on the stationary core member 26 of the tripping magnet 5 and is adapted to support a pin or cam member 37. The member 35 is provided with a double acting spring 38 for normally holding the member 35 in a predetermined position. The pin 37 is adapted to engage the lower surfaces 39 of the projections 25 which are so shaped that, after the pin 37 engages the same, the

movable member 35 is adapted to move in a counter-clockwise direction to cause the pin to follow the surfaces 39 until it assumes a position adjacent its upper surfaces 40 and becomes lodged between the cam surface 16 5 and the surfaces 40 to thus hold the lever 19 in its closed position. It will be understood that the projections 25 are so separated as to permit the member 35 to pass between them.

Assuming that the circuit interrupter is in 10 the position shown in Fig. 1 of the drawings and that it is desired to trip the same, the winding 28 of the tripping magnet is energized and its movable core member 27 rises 15 and causes the rod 29 to engage the projection 23 on the latch 21; thus releasing the pin 17 and permitting the lever 11 to move upwardly. After the lever 11 has moved to 20 such position that the pin 37 does not engage the cam surface 16, the member 35 will be moved in a clockwise direction and the pin 37 will pass over the surfaces 40 of the 25 projections 25 until it assumes the position shown in the dot-and-dash lines in the drawings. This will permit the lever 19 to be moved upwardly by springs 41 that are connected between projections 42 on the lever 19 and the stationary core member 8 of the electromagnet 7.

When the lever 19 moves upwardly, the 30 latch 21 will again engage the pin 17, and, if it is desired to reclose the circuit interrupter 1, the winding 10 of the electromagnet 7 is energized. When the winding 10 is energized, the movable core member 9 is moved 35 downwardly until the pin 37 in the member 35 slides over the surfaces 39 and 40 of the projections 25 to such position that it becomes lodged between the cam surface 16 of the lever 11 and the surfaces 40 of the 40 projections 25, as hereinbefore set forth. However, if such conditions obtain on the circuit to which the interrupter is connected as to render closure of the interrupter inadvisable, the projection 23 of the latch 21 will 45 engage the rod 29 which will permit the lever 11 to again move upwardly and the lever 19 to follow a short time afterward.

From the above, it will be understood that 50 only a single latch is employed and that no interlocking device is necessary to permit the sequential operation of the levers.

It will be further understood that my invention is not limited to the particular structure illustrated, as it may be variously modified within the spirit and scope of the appended claims.

I claim as my invention:

1. An electric switch comprising a 60 movable contact-carrying member having a pin therein and a cam surface at one of its ends, an operating lever having a cam surface and a latch for engaging the pin in the contact-carrying member, and a pivotally-mounted member having a pin therein that is adapted

to so engage the cam surface of the operating lever and to be held in such position by the cam surface of the contact-carrying member that the operating lever is held in its closed position.

2. In a circuit-closing device, the combination with two pivotally-mounted members and means for latching them together, of a pivotally-mounted spring-restrained member having a pin therein, each of the 70 pivotally-mounted members having a cam surface therein adapted to so engage the pin in the spring-restrained members that the pivotally-mounted members are secured in their closed position.

3. The combination with two pivotally-mounted levers and means for latching them together, of a pivotally-mounted member having a pin therein that is adapted to be so lodged between the two levers as to 80 hold them in a predetermined position.

4. The combination with two pivotally-mounted levers, and means for latching them together, of a pivotally-mounted member having a pin therein that is adapted to be so lodged between the two levers as to hold them in predetermined positions and to permit their successive operation when the latch that normally holds them together is released.

5. In a circuit interrupter, the combination with a contact-carrying lever and an actuating lever, of means for latching the levers together, and a pivotally-mounted member adapted to become so lodged between the two levers as to hold them in predetermined positions.

6. In a circuit interrupter, the combination with a contact-carrying lever and an actuating lever, of means for latching the levers together, and a pivotally-mounted spring-restrained member adapted to become so lodged between the two levers as to hold one of them in predetermined positions.

7. In a circuit interrupter, the combination with a contact-carrying lever and an actuating lever, of means for latching the levers together, and a pivotally-mounted spring-restrained cam member adapted to become so lodged between the two levers as to hold them in predetermined positions.

8. In a circuit interrupter, the combination with a contact-carrying lever and an actuating lever, of means for latching the levers together, a pivotally-mounted spring-restrained cam member adapted to become so lodged between the two levers as to hold them in predetermined positions, and means for releasing the latching means to release the contact-carrying lever from the other lever, said cam member being adapted to release the other lever after the contact-carrying lever has so moved as to permit the cam member to be dislodged.

9. The combination with two pivotally-

mounted levers having cam surfaces near their outer ends, of means for latching them together, and relatively stationary means adapted to become wedged between the two cam surfaces to permit the sequential operation of the levers when the latching means is released.

10. The combination with two pivotally-mounted levers having cam surfaces near

their outer ends, of means for latching them together, and relatively stationary means adapted to become wedged between the two cam surfaces to hold them in predetermined positions.

In testimony whereof I have hereunto subscribed my name this 27th day of July, 1916.

JOHN B. MacNEILL.
